Des. 189,188
Patented Nov. 8, 1960

189,188

RADIO LOUD-SPEAKER CABINET

William A. Hutton, Jr., 624 55th St. NE.,
Washington, D.C.

Filed May 27, 1960, Ser. No. 60,754

Term of patent 7 years

(Cl. D26—14)

Figure 1 is a perspective view of a radio loud-speaker cabinet, showing my new design.

Figure 2 is a rear elevational view.

Figure 3 is an end elevational view taken on the left side of Figure 2.

I claim:

The ornamental design for a radio loud-speaker cabinet, as shown.
